MASSACHUSETTS.

LOOM-SHUTTLE.

No. 855,791.

Specification of Letters Patent.

Patented June 4, 1907.

Application filed June 28, 1906. Serial No. 323,841.

To all whom it may concern:

Be it known that we, JOSEPH LACROIX and JOHN V. CUNNIFF, citizens of the United States, residing at Fall River, in the county 5 of Bristol and State of Massachusetts, have invented a new and useful Improvement in Loom-Shuttles, of which the following is a specification.

This invention has reference to an improvement in shuttles and more particularly to an improvement in hand threading devices for loom shuttles.

The object of our invention is to provide a loom shuttle with a mechanical threading device adapted to facilitate the threading of 15 the shuttle by hand, without suction.

A further object of our invention is to construct a threading device for loom shuttles so that, when threaded, the thread is positively locked in the device, thereby preventing the thread from flying out at either the throat or delivery eye of the shuttle.

A still further object of our invention is to construct a threading device for loom shuttles so that the shuttle cannot be improperly threaded.

Our invention consists in the peculiar and novel construction of a mechanical threading device for loom shuttles and the adjacent 20 portions of the shuttle, as will be more fully set forth hereinafter and claimed.

Figure 1 is a top plan view of the thread delivery end of the loom shuttle provided with our improved threading device. Fig. 2 is a side view of Fig. 1 looking at the delivery eye of the shuttle. Fig. 3 is an enlarged detail sectional view taken on line 3 3 of Fig. 2, showing the thread extending partly around the threading device and out through 25 the delivery eye. Fig. 4 is an enlarged transverse sectional view taken on line 4 4 of Fig. 1, showing the threading device in the closed or locked position, and Fig. 5 is a transverse sectional view similar to Fig. 4, 30 showing the threading device in the open position to receive the thread.

In the drawings, *a* indicates the thread delivery end of a loom shuttle, *b* the nose end portion of a bobbin in the shuttle, *c* a weft thread, and *d* our improved threading device.

The shuttle *a* has a longitudinal dished depression 6 in the top merging into the bob-

bin cavity and having the semi-circular end 7 toward the point of the shuttle, a circular chamber 8 concentric with the semi-circular end 7 and extending downward below the plane of the delivery eye of the shuttle, a smaller concentric screw-threaded hole 9 through the bottom of the chamber 8, a concentric circular recess 10 in the bottom of the shuttle, a circular hole 11 leading centrally from the bobbin cavity to the chamber 8 forming the throat, a slit 12 extending centrally downward from the depression 6 in 65 the top of the shuttle through to the hole 11, a circular hole 13 leading inward at an angle from the side of the shuttle to the chamber 8 on a plane with the hole 11 and forming the delivery eye 14 of the shuttle and a slit 15 70 extending from the hole 13 upward through the top of the shuttle and from the side of the shuttle through to the chamber 8, otherwise the shuttle may have the construction of any of the well-known forms of loom shuttles. 75

Our improved threading device *d* consists of a round hollow concave post 16 having a central hole 17 in the top forming the internal annular shoulder 18, a reduced screw-threaded open lower end 19 adapted to screw 80 into the screw-threaded hole 9 in the bottom of the chamber 8 and forming the annular shoulder 20, a vertical lug 21 on the side of the post adapted to bear on the wall of the chamber 8 intermediate the holes 11 and 14, 85 as shown in Fig. 3, a circular cap 22 slightly larger than the chamber 8 and having a smooth slightly convex top, a beveled edge 23 adapted to fit in the depression 6 in the top of the shuttle, a downwardly-extending 90 annular lip 24 adapted to have a sliding fit over the upper end of the post 16 and to form an annular space 25 between the lip 24 and the wall of the chamber 8, and a central stem 26 having the screw-threaded lower end 27 95 and adapted to extend downward from the cap through the hole 17 in the top of the post 16, a nut button 28 secured by screwing the same onto the end 27 of the stem in the recess 10 in the bottom of the shuttle and a coiled 100 spring 29 surrounding the stem in the post and engaging with the internal annular shoulder 18 in the post and the nut button 28 on the stem, as shown in Fig. 5.

In the operation of my improved threading 105 device the shuttle is held in the left hand

with the thumb on the button 28, the cap 22 is raised into the position as shown in Fig. 5 against the tension of the coiled spring 29 by a pressure of the thumb on the button 28, 5 and the thread *c* passed to the right around the cap under the beveled edge 23, and then down simultaneously through the annular space 25, the slit 15 into the hole 13, the slit 12 into the hole 11 and out through the delivery eye 14, when the pressure of the thumb on the button is removed and the cap resumes automatically its normal or locked position through the tension of the spring. The thread now leads from the bobbin 6 10 through the hole 11 or throat partly around the post 16 and out through the hole 13 and the delivery eye 14 of the shuttle, as shown in Figs. 1 and 3. The thread is prevented from jumping out of the threading device 15 first by the annular lip 24 and then by the beveled edge 23 on the cap. In threading the shuttle the thread would materially be carried to the right around the cap 22 to bring the thread around the post 16, as shown 20 in Figs. 3 and 4. If the thread should be passed to the left the lug 21 would prevent the thread from entering the hole 11 or throat of the shuttle, thereby indicating that the shuttle was improperly threaded. In practice we find that the friction of the thread 25 around the post 16 of the threading device gives the necessary amount of tension on the thread, also the post presenting a smooth round surface to the thread eliminates the liability of the thread breaking, when the shuttle is in operation.

By this construction we provide a loom shuttle with a strong and durable hand threading device giving the same action when 30 the shuttle is in operation as the older forms of shuttle, where the thread is drawn through the eye of the shuttle by suction, which can be threaded easily and quickly without failure and which having few parts is not liable 35 to get out of order or wear, the only part liable to wear being the post 16 which if worn may be renewed at a nominal expense.

Having thus described our invention, we claim as new and desire to secure by Letters 40 Patent;—

1. In a loom shuttle, a shuttle body having a dished depression in the top, a circular chamber extending down from the depression, intersecting the hole forming the throat, 45 and the hole forming the eye of the shuttle, and slits extending down from the depression and the top of the shuttle to the holes forming the throat and eye of the shuttle, a fixed circular post in the chamber, a cap 50 adapted to fit in the depression in the top of the shuttle and close the open end of the chamber, means for holding the cap in the

closed position under spring tension, and means by which the cap may be raised against the spring tension. 6

2. In a loom shuttle, a shuttle body having a dished depression in the top, a circular chamber extending down from the depression, a hole leading from the bobbin cavity into the chamber, a hole leading from the side of the shuttle into the chamber and forming the eye of the shuttle, and slits extending from the depression and the top of the shuttle to the holes leading from the bobbin cavity and the side of the shuttle, a 70 fixed round hollow post in the chamber having a screw threaded lower end, a cap adapted to fit in the depression in the top of the shuttle and close the open upper end of the chamber, a stem on the cap adapted to extend down through the post, a button on the end of the stem in the recess in the bottom of the shuttle, and a coiled spring surrounding the stem in the post, whereby the cap is held in the closed position under spring tension and may be raised by an upward pressure on the button to thread the shuttle, as 75 described. 80

3. In a shuttle, a shuttle body having a circular chamber connected with the bobbin 90 cavity and the shuttle eye, a fixed circular post in said circular chamber, a cap adapted to close the open end of the chamber, means for holding the cap yieldingly in the closed position under spring tension, and means by 95 which the cap may be raised against said spring tension. 90

4. In a loom shuttle a hand threading device *d* comprising a round hollow concave post 16 having a central hole 17 in the top 100 forming an internal annular shoulder 18, a reduced screw-threaded lower end 19 forming an annular shoulder 20, a vertical lug 21 on the side of the post, a circular cap 22 larger than the chamber 8 and having a 105 slightly convex top, a beveled edge 23 adapted to fit in the depression 6 in the top of the shuttle, a downwardly - extending annular lip 24 adapted to have a sliding fit over the upper end of the post 16, and a central stem 110 26 having a screw-threaded lower end 27, a nut button 28 on the end 27 of the stem, and a coiled spring 29 surrounding the stem 26 in the post 16 and adapted to engage with the shoulder 18 in the post and the button 28 on the stem, for the purpose as described. 115

In testimony whereof we have signed our names to this specification in the presence of two subscribing witnesses.
